Primary Examiner — Kevin Rudzinski

(57) **CLAIM**

The ornamental design for a floating hoop light fixture, as shown and described.

DESCRIPTION

FIG. 1 is a first perspective view of the new design for a floating hoop light fixture;

FIG. 2 is a side elevation view thereof;

FIG. 3 is a top plan view thereof; and,

FIG. 4 is a bottom plan view thereof.

Broken lines are used to show the mounting structure for mounting the light fixture to a wall or ceiling, which forms no part of the claimed design. In some embodiments, the mounting structures may not be visible, for example they may be mounted behind a wall or ceiling or covered with a film. Light fixtures may contain lighting within the fixture itself. For example, lights may be placed within the interior of the claimed design.
